Nelson Howard*

UNITED STATES PATENT OFFICE

FRED L. MOONEY, OF LYNN, MASSACHUSETTS, ASSIGNOR TO UNITED SHOE MACHINERY CORPORATION, OF PATERSON, NEW JERSEY, A CORPORATION OF NEW JERSEY

SHOE PRESSING MACHINE

Application filed July 25, 1929. Serial No. 380,987.

This invention relates to machines for applying pressure to the bottoms of shoes, and is herein illustrated as embodied in a machine of that type in which the pressure is applied 5 at one time to all the portions of the shoe bottom that are treated by the pressing means, by use of a yieldable pressing member or pad. The invention is also herein illustrated as applied to the shaping of the 10 shank portions of outsoles in the manufacture of shoes of a type having both an outsole and an insole with the outsole secured directly to the outer face of the margin of the upper overlying the insole; but it is to be 15 understood that it is applicable to the manufacture of shoes of various kinds including welt shoes and turn shoes. It is further to be understood that the invention is not limited to means for operating on the shank portions 20 of shoes, and that it is applicable to sole-laying operations as well as to operations performed after the soles have been secured to other portions of the shoe materials.

It is a characteristic of shoes of certain 25 kinds or styles, especially of some women's shoes, that the shank portions of the soles have pronounced lateral curvatures and are provided with thin edges lying in close relation to the uppers. For shaping the shank 30 portion of the sole of a shoe of that kind there are advantages in the use of pressing means that acts at one time on all the portions of the sole that it treats, as distinguished, for example, from a roll which is preferably used 35 at the forepart to shape that portion of the sole progressively, as explained in Letters Patent No. 1,790,191, granted on January 27, 1931, upon an application of E. E. Winkley. In order to impart to the shank portion of 40 the sole the required lateral curvature and to press its edges into close relation to the upper, it is necessary in the use of such pressing means that heavy pressure be applied at the opposite sides of the shoe bottom in locations at and near the edges of the sole. Accordingly, in one important aspect, an object of this invention is to provide pressing 45 means of such a character as to produce improved results in respect to the application of pressure at the sides of the shoe bottom. For

the purpose in view, the construction herein shown comprises a pad holder having opposite side portions arranged to support a pressing pad in locations opposite the bottom of a shoe to which the pressure is applied and arranged to tip in response to the pressure of the shoe on the pad in such manner as to cause an increase of pressure in the vicinity of the side edges of the sole. More particularly, in one aspect, the construction 55 shown is such as to afford provision, by the tipping of the opposite side portions of the pad holder, for an increase in the yield of portions of the pad located midway between the opposite side edges of the shoe bottom 60 relatively to other portions of the pad, so that the shoe sinks farther into the pad than it otherwise would, with resulting increase in the pressure at the sides of the shoe bottom. It is a further advantageous characteristic 65 of the construction shown that by the tipping of the side portions of the pad holder there is effected, to some extent, a lateral compression of portions of the pad that are adjacent to the shoe and also a bending of the pad as 70 a whole in such manner as to wrap it around the laterally convex surface of the shank portion of the shoe bottom. In these different ways a relative increase is effected in the pressure of the pad in locations at and near 75 the edges of the sole, so that the sole is conformed effectively to the latterly convex contour of the bottom of the shank portion of the last and its edges are pressed close to the upper in the manner required for the best 80 results.

The invention will now be more particularly described by reference to the accompanying drawing and thereafter pointed out in the claims.

In the drawing,

Fig. 1 is a perspective view of a portion of a machine in which the invention is embodied, showing a shoe under pressure in the machine;

Fig. 2 is a vertical section widthwise of the shoe, illustrating more fully the construction and manner of operation of parts of the machine; and

Fig. 3 is a vertical section lengthwise of

the shoe, illustrating further the relation between the shoe and the parts that operate thereon.

The invention is illustrated as applied to a machine of the same type as that disclosed in Letters Patent No. 1,549,243, granted on August 11, 1925, upon an application of E. E. Winkley, with portions of the machine constructed in accordance with the further disclosure of Letters Patent No. 1,790,192, granted on January 27, 1931 upon an application of E. E. Winkley; although it is to be understood that the invention is not limited to machines of that particular type. Machines of the type referred to are twin machines, comprising duplicate mechanisms whereby one shoe is subjected to pressure simultaneously with the release from pressure of another shoe previously operated upon. Only one of such mechanisms is herein illustrated or need be referred to for an understanding of the present invention. As shown in Fig. 1, and as more fully illustrated in Letters Patent No. 1,549,243 above mentioned, the machine is provided with a pair of vertical rods 10 on which there is adjustably secured a casting 12 which serves as a support for downwardly extending arms 14 and 16 of a jack which supports the shoe against the upwardly directed pressure of the sole-pressing means. The arm 14 is provided with a pin 17 (Fig. 3) for engaging the heel end of the last in its spindle hole, and the arm 16 is provided with means of the same construction as disclosed in the above-mentioned Letters Patent No. 1,790,192 for supporting the last and shoe along the instep and in the hollow back of the toe.

Mounted for vertical sliding movement on the rods 10 is a carrier 18 provided at its opposite sides with means for supporting a pair of trunnions 20 that are fast on a pad box 22, this pad box being provided with means more particularly hereinafter described for supporting a pressing pad 24 whereby pressure is applied to the bottom of the shoe. The means for imparting operative movement to the carrier 18 includes a link 26 and other mechanism not herein shown in detail, since it is fully disclosed in the above-mentioned Letters Patent No. 1,549,243. It will be understood that the shoe is mounted on the jack by the operator when the carrier 18 is in its lowermost position, and that in the operation of the machine the carrier and the shoe-pressing means supported thereon are moved upwardly to apply the pressure to the shoe, after which the machine comes automatically to rest. In the next operation of the machine the shoe is released by downward movement of the carrier 18 simultaneously with the application of pressure to another shoe by the other twin mechanism.

The invention is illustrated by reference to a sole-pressing operation performed mainly on the shank portion of the bottom of a

woman's shoe having characteristics such as hereinbefore described, the arrangement of the jack parts 14 and 16 and of the pressing means being such that the pressure is applied in a direction inclined somewhat forwardly toward the forepart of the shoe, in general similarity to the disclosure of Letters Patent No. 1,790,192. The bottom of the shank portion of the last, as illustrated, has a pronounced lateral curvature, and the outsole has comparatively thin edges which should lie close to the upper in the finished shoe. For shaping the shank portion of the outsole to the contour of the last and for pressing its edges close to the upper, the machine is provided, for purposes of this invention, with a pad holder which is divided centrally lengthwise of the shoe to form relatively movable opposite side portions or halves 28 each constructed to engage and support the pressing pad 24 in a location underneath it or opposite the bottom of the shoe and also to engage a side face of the pad. The opposite side portions 28 of the pad holder are pivotally supported on the pad box 22 by means of rods 30 located at the opposite sides of the pad 24 near the top of the pad, so that each side portion 28 may tip relatively to the other about an axis extending lengthwise of the shoe, the arrangement shown being such that the tipping movements occur in response to pressure of the shoe on the pad and against the resistance of springs 32 mounted in the pad box 22 and engaging arms 34 on the members 28. Preferably each member 28 is provided with two arms 34 in engagement with separate springs 32, and each spring at its outer end is seated on an abutment screw 36 in the pad box whereby its tension may be varied. Initially the springs 32 position the two halves 28 of the pad holder in abutting relation to each other with the portions that underlie the pad in the same plane, and in the sole-pressing operation the springs yield more or less in response to such tipping movements of the parts 28 as occur in response to pressure of the shoe on the pad 24. The pad 24 is preferably made of rubber with a leather cover on its shoe-engaging face, as common heretofore, and it may, as illustrated, be shaped to approximate more or less closely the contour of the portions of the shoe bottom on which it is to operate, in accordance also with prior practice.

By reference to Fig. 2 it will be seen that with the rods 30 located as shown near the top of the pad 24 at its opposite sides, the tipping movements of the members 28 of the pad holder result in a lowering of the portions of the holder which are under the central portion of the pad relatively to other portions, in relative separation widthwise of the shoe of the lower portions of the members 28, and in some relative movement toward each other of the extreme upper portions of

the members 28 at the sides of the pad. Consequently, the construction disclosed provides for increase in the yield of portions of the pad located centrally under the shoe bottom relatively to other portions, both by reason of the lowering of the intermediate portions of the pad holder and by reason of the greater room afforded for lateral expansion of the lower portions of the rubber pad, so that the shoe is permitted to sink farther into the pad than it otherwise would, with a resulting increase in the pressure applied in the vicinity of the side edges of the sole. Furthermore, the inward tipping movements of the upper portions of the members 28 at the sides of the pad result in more or less lateral compression of portions of the pad that are adjacent to the shoe, with a further tendency to increase the pressure at the sides of the shoe bottom. It will also be observed that the effect is to bend the pad as a whole in such manner as to produce a wrapping effect around the laterally convex surface of the shank portion of the last bottom. In these different ways there is produced a relative increase in the amount of pressure applied to the sole adjacent to its opposite side edges while adequate pressure is still maintained on other portions of the sole, so that insurance is afforded that the sole will be shaped properly in conformity to the curvature of the bottom of the last and that its opposite side edges will be pressed into the desired close relation to the upper.

It is to be understood that the invention is not limited to a construction in which the axes about which the different portions of the pad holder tip are located in the particular relation to the pad and the holder herein illustrated, and that in other respects also variations in the construction and arrangement of parts may be made consistently with the results which it is sought to accomplish.

Having thus described my invention, what I claim as new and desire to secure by Letters Patent of the United States is:

1. In a machine for applying pressure to soles on the bottoms of shoes, the combination with means for supporting a shoe against pressure on its bottom face, of sole-pressing means constructed to apply its pressure at one time to substantially all the portions of the sole that are treated by said means and comprising parts arranged to act respectively on opposite side portions of the shoe bottom to apply their pressure in directions heightwise of the shoe over the greater portion of the width of the sole and mounted to tip relatively to each other in the sole-pressing operation in such directions as to effect an increase of pressure on the shoe bottom in the vicinity of the opposite side edges of the sole.

2. In a machine for applying pressure to soles on the bottoms of shoes, the combina-

tion with means for supporting a shoe against pressure on its bottom face, of sole-pressing means constructed to apply its pressure at one time to substantially all the portions of the sole that are treated by said means and comprising parts arranged to act respectively on the opposite side portions of the shoe bottom to apply their pressure in directions heightwise of the shoe over substantially the whole width of the sole and mounted to tip relatively to each other, in response to pressure of the shoe on said pressing means, about axes extending lengthwise of the shoe to effect an increase of pressure at or near the opposite side edges of the sole.

3. In a machine for applying pressure to soles on the bottoms of shoes, a sole-pressing pad, and a pad holder comprising members arranged to engage the pad respectively in different locations nearer together than the opposite side edges of the bottom of a shoe to which the pressure is applied and mounted to tip relatively to each other in the sole-pressing operation in directions such as to effect an increase of pressure on the shoe bottom in the vicinity of the opposite side edges of the sole.

4. In a machine for applying pressure to soles on the bottoms of shoes, a sole-pressing pad, and a pad holder comprising members arranged to engage the pad respectively in different locations opposite the bottom of a shoe to which the pressure is applied, said members being so mounted as to tip relatively to each other, in response to pressure of a shoe on the pad, in directions such as to effect an increase of pressure at or near the opposite side edges of the sole, and means for yieldingly opposing the tipping of said members.

5. In a machine for applying pressure to soles on the bottoms of shoes, a sole-pressing pad, and a pad holder comprising members arranged to support respectively the opposite side portions of the pad in locations under the bottom of a shoe to which the pressure is applied and mounted to tip relatively to each other in the sole-pressing operation in directions such as to effect an increase of pressure on the bottom of the shoe in locations adjacent to the opposite side edges of the sole.

6. In a machine for applying pressure to soles on the bottoms of shoes, a sole-pressing pad, and a pad holder comprising members arranged to support respectively the opposite side portions of the pad in locations opposite the bottom of a shoe to which the pressure is applied and mounted to tip relatively to each other, in response to pressure of the shoe on the portions of the pad supported by said members, about axes extending lengthwise of the shoe to effect an increase of pressure in the vicinity of the opposite side edges of the sole.

7. In a machine for applying pressure to soles on the bottoms of shoes, a sole-pressing pad arranged to extend across the bottom of a shoe, and a pad holder comprising opposite side portions arranged to underlie the pad in locations opposite the bottom of the shoe and mounted to tip respectively in the sole-pressing operation about axes extending lengthwise of the shoe and spaced apart widthwise of the shoe to effect an increase of pressure on the shoe bottom in the vicinity of the opposite side edges of the sole. 70
8. In a machine for applying pressure to soles on the bottoms of shoes, a sole-pressing pad arranged to extend across the bottom of a shoe, and a pad holder comprising opposite side portions arranged to engage the pad at its sides and also in locations opposite the bottom of the shoe and mounted to tip, in response to pressure of the shoe on the pad, each about an axis extending lengthwise of the shoe to effect an increase of pressure in the vicinity of the opposite side edges of the sole. 75
9. In a machine for applying pressure to the shank portions of soles on the bottoms of shoes on their lasts to shape them to the laterally convex curvatures of the bottoms of the lasts, a sole-pressing pad so formed and arranged as to limit it substantially to engagement with a shoe at the rear of the fore-part, and a pad holder comprising opposite side portions arranged to tip relatively to each other in the sole-pressing operation to wrap the pad around the laterally convex curvature of the shank portion of the last bottom. 80
10. In a machine for applying pressure to the shank portions of soles on the bottoms of shoes on their lasts to shape them to the laterally convex curvatures of the bottoms of the lasts, a sole-pressing pad so formed and arranged as to limit it substantially to engagement with a shoe at the rear of the fore-part, and means operative in response to pressure of the shoe on the pad to bend the pad as a whole around the laterally convex curvature of the shank portion of the last bottom. 85
11. In a machine for applying pressure to the bottoms of shoes, the combination with means for supporting a shoe against pressure on its bottom face, of pressing means constructed to apply its pressure at one time to substantially all the portions of the shoe bottom that are treated by said means and comprising parts arranged to act respectively on the opposite side portions of the shoe bottom in locations extending inwardly from the edges of the shoe bottom to apply their pressure in directions heightwise of the shoe and mounted to tip relatively to each other in the pressing operation each about an axis extending lengthwise of the shoe to effect an increase of pressure at the opposite side edges of the shoe bottom. 90
12. In a machine for applying pressure to the bottoms of shoes, a shoe-pressing pad, and a pad holder comprising members arranged to engage respectively the opposite side portions of the pad in locations nearer together than the opposite side edges of the bottom of a shoe to which the pressure is applied and mounted to tip in the pressing operation each about an axis extending lengthwise of the shoe. 95
13. In a machine for applying pressure to the bottoms of shoes, a shoe-pressing pad arranged to extend across the bottom of a shoe, and a pad holder comprising members arranged to engage respectively the opposite side portions of the pad in locations opposite the bottom of the shoe and mounted to tip respectively in the pressing operation about axes extending lengthwise of the shoe and spaced apart widthwise of the shoe. 100
14. In a machine for applying pressure to the bottoms of shoes, a shoe-pressing pad, and a pad holder comprising opposite side portions arranged to support the pad in locations opposite the bottom of a shoe to which the pressure is applied and mounted to tip in the pressing operation about axes extending lengthwise of the shoe and located at the sides of the pad. 105
15. In a machine for applying pressure to the bottoms of shoes, a shoe-pressing pad, and a pad holder divided substantially midway between its opposite sides to provide two pad-supporting portions, the two portions of the holder being mounted to tip in the pressing operation each about an axis extending lengthwise of a shoe to which the pressure is applied. 110
16. In a machine for applying pressure to the bottoms of shoes, a shoe-pressing pad, and a pad holder divided centrally lengthwise of a shoe to which the pressure is applied to provide opposite halves constructed to engage the pad at its sides and also in locations opposite the bottom of the shoe, the two halves of the pad holder being mounted to tip in the pressing operation each about an axis extending lengthwise of the shoe. 115
17. In a machine for applying pressure to the bottoms of shoes, a shoe-pressing pad, and a pad holder divided centrally lengthwise of a shoe to which the pressure is applied to provide opposite halves constructed to engage the pad at its sides and also in locations opposite the bottom of the shoe, the two halves of the pad holder being mounted to tip relatively to each other in the pressing operation about axes extending lengthwise of the shoe and located near the top of the pad. 120
18. In a machine for applying pressure to the bottoms of shoes, a shoe-pressing pad, and a pad holder comprising opposite side portions each formed to engage a side face of the pad and also to underlie the pad and 125

the bottom of the shoe, the different portions of the pad holder being mounted to tip in the pressing operation each about an axis extending lengthwise of a shoe to which the pressure is applied.

19. In a machine for applying pressure to the bottoms of shoes, flexible shoe-pressing means, and a support for said means comprising parts having a component of relative movement widthwise of a shoe in the pressing operation to increase the yield of portions of the pressing means located midway between the opposite sides of the shoe relatively to other portions of said means.

20. In a machine for applying pressure to the bottoms of shoes, a shoe-pressing pad, and a pad holder comprising portions arranged to support each substantially a half of the pad in a location opposite the bottom of a shoe to which the pressure is applied and movable relatively to each other in the pressing operation to increase the yield of portions of the pad located centrally of the shoe bottom relatively to other portions of the pad.

21. In a machine for applying pressure to the bottoms of shoes, a shoe-pressing pad of yieldable material, and a pad holder divided lengthwise of a shoe to which the pressure is applied and constructed to engage the pad at its sides and also in locations opposite the bottom of the shoe, the two portions of the divided pad holder being mounted to tip relatively to each other, in response to pressure of the shoe on the pad, in such directions as to increase the yield of portions of the pad located centrally of the shoe bottom relatively to other portions and also to effect lateral compression of portions of the pad located adjacent to the shoe.

22. In a machine for applying pressure to the bottoms of shoes, a shoe-pressing pad of yieldable material, and a pad holder divided lengthwise of a shoe to which the pressure is applied and constructed to engage the pad at its sides and also in locations opposite the bottom of the shoe, the two portions of the divided pad holder being mounted to tip relatively to each other in the pressing operation about axes extending lengthwise of the shoe and so located as to effect lateral compression of portions of the pad adjacent to the shoe and to afford increased room for lateral expansion of portions of the pad remote from the shoe in the direction of its height.

23. In a machine for applying pressure to the bottoms of shoes, a shoe-pressing pad of yieldable material arranged to operate on the bottom of a shoe, and means automatically operative in the pressing operation to effect compression widthwise of a shoe to which the pressure is applied of portions of the pad adjacent to the shoe while affording increased room for widthwise expansion of portions of

the pad located more remote from the shoe in the direction of its height.

24. In a machine for applying pressure to the bottoms of shoes, a shoe-pressing pad, and means arranged to engage the pad and automatically movable in the pressing operation to bend the pad as a whole across the bottom of a shoe to which the pressure is applied.

25. In a machine for applying pressure to the bottoms of shoes, a shoe pressing pad, and members arranged to control respectively the opposite side portions of the pad and movable in response to pressure of a shoe on the pad to bend the pad as a whole across the bottom of the shoe.

26. In a machine for applying pressure to the bottoms of shoes, a shoe-pressing pad, and a pad holder comprising members arranged to engage respectively the opposite side portions of the pad in locations nearer together than the opposite side edges of the bottom of a shoe to which the pressure is applied and relatively movable in directions such as to wrap the pad about the bottom of the shoe.

27. In a machine for applying pressure to the bottoms of shoes, a shoe-pressing pad, and a pad holder having opposite side portions arranged to engage the pad in locations opposite the bottom of a shoe to which the pressure is applied, the opposite side portions of the pad holder being movable, in response to pressure of the shoe on the portions of the pad engaged by the holder, about axes extending lengthwise of the shoe to wrap the pad about the laterally convex surface of the shank portion of the shoe bottom.

28. In a machine for applying pressure to the bottoms of shoes, a shoe-pressing pad of yieldable material so formed and arranged as to limit it substantially to engagement with a shoe at the rear of the forepart and a pad holder comprising opposite side portions mounted to tip relatively to each other in the pressing operation in such manner as to bend the pad as a whole across the bottom of the shoe.

In testimony whereof I have signed my name to this specification.

FRED L. MOONEY.
